COMBINATION SHELF AND DISPENSER

Michael Saphier, New York, N. Y.

Application January 13, 1955, Serial No. 33,966

Term of patent 14 years

(Cl. D4—3)

FIG. 1

I claim:

The ornamental design for a combination shelf and dispenser, as shown and described.
